UNITED STATES PATENT OFFICE.

CHARLES NELSON, OF NEW YORK, N. Y., ASSIGNOR TO S. STERNAU & COMPANY, A
COPARTNERSHIP COMPOSED OF SIGMUND STERNAU AND LIONEL STRASSBURGER,
OF BROOKLYN, NEW YORK.

ALCOHOL-LAMP.

Specification of Letters Patent. Patented Sept. 21, 1915.

1,154,125.

Application filed April 11, 1914. Serial No. 831,253.

To all whom it may concern:

Be it known that I, CHARLES NELSON, a citizen of the United States, residing in the borough of Brooklyn, county of Kings, city 5 and State of New York, have invented a certain new and useful Alcohol-Lamp, of which the following is a specification.

The object I have in view is the production, in a lamp for burning alcohol or other 10 spirits by means of a wick and more particularly to that form of lamp in which the size of the flame is regulated by a vertically movable sleeve which more or less masks the flame openings in the wick tube, of improved 15 means for supporting and securing in place the means for manipulating the masking sleeve, which will be cheaper, stronger and more durable than the devices now in use. This and further objects will more fully appear 20 from the following specifications and accompanying drawings considered together or separately.

In the drawings, Figure 1 is a plan view of my improved lamp; Fig. 2 is a transverse 25 section of the same taken on the line 2, 2 of Fig. 1; Fig. 3 is a detail view on an enlarged scale, of the spindle and sleeve; Fig. 4 is a section on the line 4, 4 of Fig. 3; Fig. 5 is a sectional view of a modification; and 30 Fig. 6 is a detail view showing the manner of securing the bearing to the font.

In all of the above views, like parts are represented by similar reference characters.

The lamp, in the embodiment of the invention, chosen for illustration, embodies the 35 usual font 1, which carries a wick tube 2, a flame controlling sleeve 3 and a spindle 4. The wick tube is provided with the usual wick 5, flame openings 6 and gas outlets 7. 40 and it may be covered by the usual cap 8. The controlling sleeve 3 is provided with a vertical series of slots 9 which are engaged by a pinion 10 on the inner end of the spindle, whereby the sleeve may be raised 45 and lowered by the rotation of the spindle. The spindle is provided with a finger piece by means of which it may be manipulated.

The spindle is carried in a tube or bearing 11 which pierces the side of the font top 50 and extends inward toward the center of the font to thereby offer a long bearing for the spindle. The top of the font is stamped or otherwise forced up and into a shape corresponding to that of the outside of the tube 55 11 as shown at 12, and the projection or

forced up portion is perforated so that the tube may be passed into the interior of the font. The tube is soldered, brazed or otherwise permanently secured to the inside of the cavity formed by the projection 12, as 60 at 13, whereby a much stronger construction is secured than if the projection is not present and the tube is soldered in a perforation in a more or less vertical part of the top, and the part to which it is soldered is no 65 greater than the thickness of the stock of which the font is formed, as is the usual construction.

The pinion 10 is of a diameter no greater than the diameter of the spindle therefore 70 making it possible to insert the spindle and pinion through the tube from the outside and, when in position, the pinion will engage the slots 9 and hold the sleeve 3 in alinement.

The manner of securing the spindle in the sleeve is as follows: The spindle is provided with a circumferential groove 13', a thimble 14 is placed over the outer end of the tube and its end 15 is spun or otherwise turned 80 over so as to engage the groove. The tube 11 near its outer end is provided with a perforation 16 and the thimble 14 is secured to the tube by means of a small indentation which enters the perforation 16. This indentation may be made by a punch or a like instrument. The inturned end of the thimble will securely hold the spindle against longitudinal movement and the frictional engagement of the spindle with the tube will 85 be sufficient to retain the sleeve 3 in any desired position.

Should it become necessary at any time to remove the thimble, it may be readily cut or filed apart and removed from the sleeve 11, 90 when the spindle can be withdrawn, and when the parts are reassembled a new thimble can be secured in place at very slight expense.

In the modification shown in Fig. 5, the 100 end 17 of the tube 11 is turned over into the groove 13'. In this construction the thimble is dispensed with and a cheaper device is produced.

In accordance with the provisions of the 105 patent statutes, I have described the principle of my invention, together with the apparatus which I now consider to represent the best embodiment thereof; but I desire to have it understood that the apparatus shown is 110

merely illustrative and that the invention may be carried out in other ways.

Having now described my invention, what I claim as new and desire to secure by Letters Patent, is:

1. A lamp having a controlling shaft or spindle, a groove in the shaft or spindle, a sleeve surrounding the shaft and having its end turned into the groove to prevent longitudinal movement of the shaft.
2. A lamp having a controlling shaft or spindle, a groove in the shaft, a bearing for the shaft, a thimble on the bearing having its end projecting into and engaging the groove to prevent longitudinal movement of the shaft.
3. A lamp having a controlling shaft or spindle, a groove in the shaft, a bearing for the shaft, a thimble on the bearing, a lip on

the thimble for engagement with the groove, a perforation in the bearing, and an indentation in the thimble for engagement with the perforation.

4. A lamp comprising a font, a controlling shaft, a peripheral groove in the shaft, a bearing for the shaft, a cavity in the font for receiving the bearing, means for securing the bearing to the wall of the cavity, the end of the bearing being turned over into the groove to prevent longitudinal movement of the shaft.

This specification signed and witnessed this 3rd day of April, 1914.

CHARLES NELSON.
